(57) **CLAIM**

The ornamental design for a storage visor for compact discs, as shown and described.

DESCRIPTION

FIG. 1 is a front perspective view of a storage visor for compact discs showing my new design, the dashed lines representing stitching and forming no part of the claimed design;

FIG. 2 is a top plan view of the invention illustrated in FIG. 1;
FIG. 3 is a left elevation view of the invention shown in FIG. 1;

FIG. 4 is a right elevation view of the invention illustrated in FIG. 1;

FIG. 5 is a front elevation view of the invention illustrated in FIG. 1;

FIG. 6 is a bottom plan view of the invention illustrated in FIG. 1;

FIG. 7 is a top plan view of the invention illustrated in FIG. 1, shown in an open position;

FIG. 8 is a left elevation of the invention illustrated in FIG. 7;
FIG. 9 is a right elevation view of the invention illustrated in FIG. 7;

FIG. 10 is a front elevation view of the invention illustrated in FIG. 7;

FIG. 11 is a top plan view of the invention illustrated in FIG. 7;

FIG. 12 is a rear elevation view of the invention illustrated in FIG. 7;

FIG. 13 is a front perspective view of an alternative embodiment of the present invention;

FIG. 14 is a top plan view of the invention illustrated in FIG. 13;

FIG. 15 is a left elevation view of the invention illustrated in FIG. 13;

FIG. 16 is a right elevation view of the invention illustrated in FIG. 13;

FIG. 17 is a front elevation view of the invention illustrated in FIG. 13;

FIG. 18 is a bottom plan view of the invention illustrated in FIG. 13;

FIG. 19 is a top plan view of the invention illustrated in FIG. 13, shown in an open position;

FIG. 20 is a left elevation view of the invention illustrated in FIG. 19;

FIG. 21 is a front elevation view of the invention illustrated in FIG. 19;

FIG. 22 is a right elevation view of the invention illustrated in FIG. 19;

FIG. 23 is a bottom plan view of the invention illustrated in FIG. 19; and,

FIG. 24 is a rear elevation view of the invention illustrated in FIG. 19.
